UNITED STATES PATENT OFFICE

2,453,664

CONTAINER AND CLOSURE THEREFOR

John Hohl, Toledo, Ohio, assignor to Owens-
Illinois Glass Company, a corporation of
Ohio

Application January 19, 1946, Serial No. 642,285

5 Claims. (Cl. 215—40)

1

The present invention relates to improvements in containers and more especially glass jars, or the like, which are intended to be hermetically sealed by means of a metal closure.

An important object of my invention is the provision of a complete package in which the closure may be applied and affixed to the container quite rapidly and with positive assurance of a reliable hermetic seal, yet may with comparative ease be removed to permit access to the 10 contents. To date this combination of advantages has been unavailable, that is, if the closure provides an absolutely reliable seal, it is difficult to remove and on the other hand if the closure is readily removable, it is incapable of performing the necessary sealing function. I have overcome these objections and succeeded in my efforts to develop a package which both preserves the contents and permits ready removal of the closure, when desired.

Another object of my invention is the provision of a package in which the closure maintains a satisfactory seal irrespective of whether the container is vacuumized, or subjected to relatively high internal pressure, yet may be easily removed with a prying implement.

It is also an object of my invention to provide a package wherein the closure, sealing surface and closure retaining means are such that excessive internal pressure may be vented to the atmosphere without affecting the hermetic seal, other than to break it momentarily incident to the venting step.

It is likewise an object of my invention to provide a glass container having a closure retaining bead, or rib, embodying venting means which bead contributes materially to the retention of an hermetic seal, while the venting means permits venting of excess pressure and facilitates removal of the closure. With respect to the latter step, experience teaches that in opening a vacuumized coffee container, in which internal pressure has developed for example, where the closure is other than the screw threaded type, the closure blows off violently incident to upward prying thereof and as a consequence the closure may injure the person opening the package, but in any event loose coffee is spilled upon the table and/or floor. In my package however, the bead, or rib, holds the closure against such blowing off and an initial complete venting takes place permitting equalization of the internal and external pressure prior to complete separation of the closure from the container. Thus I have supplied all of the various essential requirements of a perfect container.

Other objects will appear hereinafter.

In the accompanying drawings.

Fig. 1 is a side elevational view illustrating my invention.

Fig. 2 is a view similar to Fig. 1 but shows one

2

edge of the closure pried up to vent just prior to complete removal of said closure.

Fig. 3 is a fragmentary vertical transverse sectional view showing the container and closure providing an hermetically sealed package, the closure being held in place solely by vacuum.

Fig. 4 is a fragmentary detail vertical sectional view similar to Fig. 3 showing the closure partially lifted from its sealing position as in Fig. 2.

Fig. 5 is a view similar to Fig. 3, but shows the closure elevated by internal pressure and mechanically secured against such displacement as would completely break the hermetic seal.

Fig. 6 is a view similar to Fig. 5, but shows the cap position when venting high pressure.

Fig. 7 is a top plan view of the container showing the venting grooves.

Fig. 8 is a fragmentary detail sectional view showing a container and closure especially designed for packaging processed foods, etc., the closure being illustrated in the position occupied when the container is properly vacuumized.

Fig. 9 is a view similar to Fig. 8, but shows the closure in its outermost sealing position which is assumed incident to a substantial decrease in the degree of vacuum.

Fig. 10 is a detail sectional view of a modified form of my invention.

In the preferred embodiment of my invention, the container, or jar 10, which may be formed of glass, or other preferred material, includes a neck 11, a pry-off shoulder 11^a and head 12 of a circular contour, defining a filling and discharge opening 13 and a slip-over side seal closure 14 intended to hermetically seal the container under any of varying conditions to which the package may be subjected. In the latter connection I particularly have in mind that the seal will be maintained in the presence of either vacuum, or pressure, within the container, as well as at high altitudes, where other types of closures (screw threaded closures excepted) blow off and break the seal because of the rarefied atmosphere encountered at such altitudes.

With respect to the container per se, the head 12 thereof includes an annular external retaining bead, or rib 15, generally semi-circular in cross-sectional shape and positioned so that its upper margin merges into the outer end surface 50 of the container head 12. The major upper portion 16 of this rib is formed on a longer radius than the lower portion 17 in order to provide a satisfactory guiding surface facilitating application of the closure 14. The lower portion 17 is formed on a relatively short radius and consequently provides effective holding means for engagement with the closure, as will be apparent and discussed in some detail hereinafter.

Spaced immediately below this bead, or rib, is 55 an annular primary sealing surface 18, which

preferably, is substantially normal to the radius of the filling opening, although it may, in practice, taper inwardly or outwardly and downwardly at a very obtuse angle or perhaps assume a slightly convex contour incident to setting of the glass in the mold. The major diameter of this primary sealing surface preferably is slightly greater than that of the bead, but incident to any tapering inwardly bisects an imaginary line extending downwardly from the crown of the bead and parallel with the axis of the container.

An auxiliary, or secondary sealing surface 19 merges with the upper margin of the first named primary sealing surface 18. This secondary sealing surface 19 is inclined upwardly and inwardly, merging at its upper margin with a short radius which connects it to the surface of the bead, or rib 15. This radius, or curved surface, or at least a major part thereof, constitutes a stop, or abutment 20, with which the closure is engaged at times and by means of which it is secured against premature removal, or blowing off, as will be brought out hereinafter. Thus I provide an annular groove, or channel 21, lying between the retaining bead 15 and the primary sealing surface 18 and utilize one wall (the lower) of the groove in forming a part of the secondary sealing surface, which, under certain conditions to be described, cooperates with the closure in maintaining hermetic sealing of the container.

The rib, or bead, is provided with an annular series of venting channels, or grooves 21*, which function to release excess pressure created within the container and/or admit outside air incident to initial prying up of the closure as a preliminary to completely removing the latter from the container. Each of these venting channels is of somewhat greater depth than the retaining bead, that is, its bottom is located radially inward from the base of the bead, considering such base to be in vertical alignment, or in the same vertical plane, with the bottom of the annular groove 21, with which each venting channel is in direct communication. Preferably the lower part of the channel bottom curves outwardly and downwardly and merges with the upper margin of the secondary sealing surface 19 which in part constitutes a portion of the lower wall of the annular groove 21. The function of these elements will be apparent hereinafter.

The closure 14 for this container preferably is formed of sheet metal, although other suitable material may be employed. It consists of a circular top 22, a depending annular skirt, or flange 23 and a sleeve type compressible sealing gasket 24, the latter formed of rubber, or a rubber-like composition. The skirt includes a substantially cylindrical upper portion 25 and an outwardly flared lower part 26, the latter accommodating a major part of the gasket which lies against said flared part and is secured against independent bodily movement upward by means of a hollow bead 27 which securely clinches, or grips, the lower margin of the gasket. The adjacent portions of both the cylindrical upper part and the flared lower part constitute a gasket constricting, or compressing means between which and the primary, or secondary sealing surface, or both, the gasket is sufficiently compressed to provide an hermetic seal.

It is of vital importance that the juncture point of the upper cylindrical part and lower flared part of the skirt be so related to the top portion of the closure and primary sealing surface of the container, that at such times as it is desired to

5 maintain an hermetic seal, this point will be positioned substantially opposite to said primary sealing surface, or at least opposite its juncture with the secondary sealing surface. Otherwise 10 insufficient compression of the gasket would be obtained and the necessary hermetic seal could not be effected. Assuming that the container has been filled with coffee, for example, the closure, 15 in the presence of vacuum, is applied and affixed simply by positioning it upon the container head and then applying top pressure thereto. Thus the closure assumes the position illustrated in Fig. 3 of the drawings wherein the gasket is compressed against the primary sealing surface. 20 So long as sufficient vacuum is maintained, it alone retains the closure in the initial sealing position. If however, vacuum is lost, or reduced to a negligible degree, the inherent plastic flow characteristic of the gasket (a rubber, or rubber-like compound) causes the closure to slide upward until the gasket enters the annular groove, or channel 21, and contacts the abutment 20. Thereafter, 25 this abutment, or stop, mechanically secures the closure against premature removal and at this point the secondary sealing surface 19 functions together with a portion of the primary sealing surface in maintaining the hermetic seal.

30 Should excessive internal pressure build up within the container, as a result, for example, of the formation of carbon dioxide gas in a coffee package, such gas will flow through the vents 21* and momentarily separate the gasket from the secondary sealing surface as indicated in Fig. 6 and escape to the atmosphere. Since such break 35 in the seal is only momentary and merely permits the release of excess pressure, it does not affect in any manner, or degree, the hermetic sealing of the container.

When it is desired to completely remove the 40 closure for access to the contents, a prying instrument I is inserted between the pry-off ledge 11* and the bead at the bottom edge of the skirt and used as a lever to move the closure upward in a segment of its periphery. This prying operation simultaneously distorts the skirt slightly, 45 bending it more or less radially outward in this area and separates the gasket in this zone from the sealing surfaces on the container. Thus air is admitted to the container in the event it had 50 held the vacuum, or releases the internal pressure, if it existed. While this is taking place, the remainder of the gasket is, by this prying operation, drawn more tightly against the sealing surfaces, or into the other portions of the annular 55 channel, or groove 21 and against the abutment 20, thereby positively insuring against premature complete removal of the closure, or blowing off thereof. Thus I avoid spilling of the contents as well as possible injury to the person opening the 60 container or others nearby, by reason of the closure being blown into his, or her, face, for example. Prying at one or two additional circumferentially spaced points completely removes the closure.

65 In a modified form of my invention (Fig. 10) the container is provided with an external annular retaining bead, or rib 28 and pry-off ledge 29. Venting channels 30 are formed transversely of the bead. The closure includes a top portion 31 and depending skirt 32, which is constricted at its lower margin into holding engagement with the bead whereby to compress a sealing gasket 33 between the top 31 and rim 34, or sealing surface, of the container. In this instance 70 excess internal pressure will lift the closure and

gasket slightly and allow escape of such pressure to the atmosphere through the vents 30 immediately following which the gasket reseats and reseals the container without having admitted any outside air. Actual complete removal by means of a prying implement is preceded by venting as in the preferred form of our invention.

In vacuum packaging of products which do not develop pressure, as does coffee, for example, I omit the venting feature, since it is unnecessary and modify the finish, or sealing surface and bead contour and relationship between them substantially as illustrated in Figs. 8 and 9. The major upper part of the bead, or rib 37 is formed on a longer radius than the previously described bead, to provide a longer camming, or guiding, surface for centering the closure C. The primary and secondary sealing surfaces 39 and 38, respectively, are spaced below the bead, being separated from the latter by an annular groove, or channel 40, the lower wall of which merges into the secondary surface and forms a part thereof. The upper wall of the groove which merges with the lower terminus of the camming surface of the rib, or bead, provides a stop, or abutment 41 adapted for engagement with the gasket 42 in the event vacuum drops below a predetermined degree, or is lost completely. The gasket and closure are formed and assembled as previously described with the exception that the notches in the gasket clinching bead 27 are omitted.

In this form of my invention, the closure is applied in the presence of vacuum, or steam which condenses in the head space of the container and creates a vacuum, and the sealing gasket 42 initially seals against both the primary and secondary sealing surfaces. The closure is thus positioned, solely by vacuum, so that the gasket is compressed against both of these sealing surfaces simultaneously, as shown in Fig. 8.

In some instances the product being packed is cooked in the sealed containers and consequently a rather high internal pressure develops, causing the closure to move upwardly until the gasket engages the abutment 41. Thereupon such opening movement of the closure stops. Incident to cooling of the product a vacuum is formed and immediately the closure moves inward, or downward and solely by means of such vacuum, the gasket is held in engagement with the sealing surfaces. Such outward movement of the closure may also take place if the degree of vacuum drops considerably, or is lost. In this event the abutment is engaged by the gasket and mechanically holds the closure against such displacement as would break the hermetic seal.

Although the complete package embodying the above structural features will withstand very high internal pressures without breaking the hermetic seal, the closure may quite easily be removed by means of any suitable prying implement as in the preceding form of my invention, that is, by inserting the implement between the bottom edge of the skirt and shoulder on the container and using such implement as a lever. Such ease of removal, in part at least, is due to the maximum diameter of the bead, or rib, being slightly less than the maximum diameter of the sealing surfaces. As a consequence, the bead or rib, while large enough to retain the closure against removal solely by the creation of internal pressure which of course is applied equally over the entire inner surface of the closure thus rendering the entire area of the abutment effective as a retaining medium, is of such proportions and so related

to the annular groove that prying up the closure at one or two closely spaced points readily removes the same. In such removal step, the gasket is subjected to relatively high compression in the zone opposite to the prying point and only slightly compressed at the point of prying. Thus the closure is easily slipped over the bead at said point of prying.

Modifications may be resorted to within the spirit and scope of my invention.

I claim:

1. In combination, a container having a generally circular neck defining a filling opening, an annular external bead formed on the neck in close proximity to said opening, there being an annular groove immediately beneath said bead and an annular sealing surface below the groove, venting means extending across the bead into said groove, a closure for hermetically sealing the container including an attaching skirt, a sleeve gasket secured at its lower end to the lower margin of the skirt against bodily sliding movement relative thereto, said gasket adapted under some sealing conditions to contact said sealing surface

20 and under both conditions to engage both the sealing surface and said bead and thereby retain the closure against axial movement sufficient to break the hermetic seal.

2. In combination, a container having a circular wall defining a filling opening, an annular external closure retaining rib on said wall, superposed merging primary and secondary sealing surfaces encircling the wall immediately below the rib, there being an annular groove between

35 the rib and said sealing surfaces, and a venting channel extending across the rib and communicating with said annular groove, a closure comprising a top portion, a depending annular skirt, said skirt including a flared lower part and substantially cylindrical upper part, adjacent areas of both said parts constituting a gasket constricting means, a sleeve gasket lying against the flared part and extending upward into the cylindrical part and means securing the gasket against bodily movement upward.

3. In combination, a container having a circular wall defining a filling opening, an annular external closure retaining rib on said wall, superposed merging primary and secondary sealing surfaces encircling the wall immediately below the rib, there being an annular groove between the rib and said sealing surfaces, and a venting channel extending across the rib and communicating with said annular groove, a closure comprising a top portion, a depending annular skirt, said skirt including a flared lower part and substantially cylindrical upper part, adjacent areas of both said parts constituting a gasket constricting means, a sleeve gasket lying against the flared part and extending upward into the cylindrical part and means securing the gasket against bodily movement upward, the area constituting the gasket constricting means being so located with

50 respect to the top portion of the closure and the retaining rib that it is opposed to either, or both sealing surfaces when hermetically sealing the container.

4. A container including a circular neck defining a filling opening, an annular external closure retaining bead formed on the neck in close proximity to said opening, there being an annular groove immediately beneath the bead, venting means extending across said bead and opening at one end in the groove, an annular primary sealing surface spaced below said groove and an an-

nular secondary sealing surface lying between the primary sealing surface and groove and in part constituting the lower wall of the latter, a closure telescoped over the wall and comprising a circular top, a depending annular skirt, and a sleeve 5 gasket secured at its lower end to the lower margin of said skirt, and thereby held against bodily movement upward, the upper end of the gasket, when the closure is in normal sealing position under vacuum, terminating short of the secondary 10 sealing surface.

5. A container including a circular neck defining a filling opening, an annular external closure retaining bead formed on the neck in close proximity to said opening, there being an annular groove immediately beneath the bead, venting means extending across said bead and opening at one end in the groove, an annular primary sealing surface spaced below said groove and an annular secondary sealing surface lying between 20 the primary sealing surface and groove and in part constituting the lower wall of the latter, a closure telescoped over the wall and comprising a circular top, a depending annular skirt, and a sleeve gasket secured at its lower end to the lower 25 margin of said skirt, and thereby held against bodily movement upward, the upper end of the

15

gasket, when the closure is in normal sealing position under vacuum, terminating short of the secondary sealing surface, a lower portion of the skirt being flared to impart a generally frustoconical shape to the gasket whereby the diameter of the upper end thereof normally is less than the exterior surface of the bead.
